UNITED STATES PATENT OFFICE.

MAURICE NOLET, OF MANCHESTER, NEW HAMPSHIRE.

STOP-MOTION FOR ROVING-FRAMES.

No. 872,963.

Specification of Letters Patent.

Patented Dec. 3, 1907.

Application filed June 14, 1907. Serial No. 378,965.

To all whom it may concern:

Be it known that I, MAURICE NOLET, citizen of the United States, residing at Manchester, in the county of Hillsboro and State 5 of New Hampshire, have invented new and useful Improvements in Stop-Motions for Roving-Frames, of which the following is a specification.

My invention pertains to the automatic 10 stopping of roving frames; and it consists in the peculiar and advantageous full bobbin stop motion mechanism hereinafter described and particularly pointed out in the claims appended.

15 In the accompanying drawings, forming part of this specification: Figure 1 is a view of so much of a roving frame as is necessary to illustrate the preferred embodiment of my invention, and showing the parts in the 20 positions they occupy during the filling of the bobbins and immediately precedent to the automatic stoppage of the machine. Fig. 2 is an enlarged detail plan view showing the swinging latch-releasing device of my 25 improvements and the bar by which said device is carried. Fig. 3 is a side elevation of the same. Fig. 4 is a vertical section taken in the plane indicated by the line 4—4 of Fig. 2. Fig. 5 is an enlarged view of the 30 tappet through which the latch-releasing device is actuated.

Similar letters designate corresponding parts in all of the views of the drawings, referring to which:

35 A is the rectilinearly movable rack usually employed in roving frames to traverse the belt upon the cones, which being well known are not shown in the drawings. During the working of the machine the said rack A is 40 gradually moved in the direction indicated by the arrow No. 1, through the medium of the pinion B and the shaft C under the control of the usual mechanism used to regulate the winding, which being ordinary and well 45 known is not shown in the drawings.

D is the belt shifting rod which carries the means used to move the driving belt into and out of position to drive or stop the machine, and is provided with an arm E. A portion 50 only of the belt-shifting rod D is illustrated, this because the rod and the means by which it controls the belt employed are of the ordinary, well-known construction.

F is a weight usually employed in roving 55 frames. G is a cable connecting the said weight with the machine, and H is a sheave

over which said cable passes as shown. The said sheave H is carried by an arm a of a vertically swinging lever I, and this lever has two additional arms b and c; the arm b being 60 arranged to engage the arm E of the belt shifting rod D, and the arm c serving for the pivotal connection of a depending latch J. This latch J has a toe d and when the said toe is in engagement with a stationary 65 keeper K, it will be apparent that the weight F is prevented from rocking the lever I in the direction indicated by arrow No. 2. When, however, the toe d is moved laterally out of engagement with the keeper K, and 70 the latch J is free to move upward, it will be seen that the gravitation of the weight F will forcibly swing the lever I in the direction indicated by arrow No. 2, and through the medium of said lever and the belt shifting 75 rod stop the machine. The keeper K is preferably formed in a stationary upright L.

M is a shaft which derives motion through well known mechanism (not shown) from a suitable part of the machine. N is a gear 80 fixed on said shaft, and P is a vertically movable rack-bar intermeshed with the gear N and having a lateral arm R. Attached to the said arm R is an angle iron fixture S, and to the vertical arm of the said fixture is connected, preferably in an adjustable manner, an upwardly-extending bar T which is preferably provided at its upper end with an angular portion m and constitutes the tappet 85 of my improvements. Attached to the rack 90 A, preferably in an adjustable manner, is a metallic bar U, and fixed to and extending laterally from said bar is a journal V having a threaded socket r in its outer end. Loosely mounted on the said journal V and retained 95 thereon by a screw s and a washer t is a metallic hub W, and to the periphery of said hub is fixedly attached a tangentially extending arm Y and a similarly extending, comparatively-long arm Z. The rear end of 100 the arm Z is preferably extended downward at the back of the hub W so as to form a counterbalance W' the office of which is to normally hold the arms Y and Z in and return the same to the position shown in 105 Fig. 1.

In the practical use of my improvements the rack A is moved in the direction of the arrow No. 1, and at the proper time, viz: when the bobbins are full, the arm Y assumes a position above the angular portion m of the bar T, and the said bar T being

moved upward as before described, engages the arm Y and thereby moves or swings the arms Y and Z in the direction indicated by the arrow No. 3. In consequence of this the 5 long arm Z acts against the pendent latch J and disengages the toe d from the keeper K, and then the gravitation of the weight F operates to rock the lever I and move the belt-shifting rod D in the direction indicated by 10 the arrow No. 2, and in that way effects a stoppage of the machine.

It will be gathered from the foregoing that while simple and inexpensive in construction my improvements are reliable in operation 15 and are well adapted to withstand the rough usage to which the appurtenances of roving frames are ordinarily subjected.

The construction herein shown and described constitutes the preferred embodiment 20 of my invention, but it is obvious that in practice such changes in the form, construction and relative arrangement of parts may be made as fairly fall within the scope 25 of my invention as defined in the claims appended.

Having described my invention, what I claim and desire to secure by Letters-Patent, is:

1. In a roving frame, the combination of 30 a belt-shifting rod, a lever having an arm for engaging and moving the belt-shifting rod, a weight, a cable connected to the weight and passed over a guide on the lever, a latch connected to the said lever, a keeper for engaging and holding the latch against movement in one direction, a belt-traversing rack, means thereon for moving the latch out of engagement with the keeper, and a device movable at an angle to the belt-traversing 35 rack and arranged to move the said means for moving the latch.

2. In a roving frame, the combination of 40 a belt-shifting rod, a lever having an arm for engaging and moving the belt-shifting rod, a weight for swinging the said lever in one direction, a latch connected to the lever, a keeper for engaging and holding the latch 45

against movement in the said direction, a belt-traversing rack, swinging arms carried by the said rack; one of said arms being arranged to move the latch out of engagement with the keeper, and a device movable at an angle to the rack and arranged to engage the other arm. 50

3. In a roving frame, the combination of 55 a belt-shifting rod, a lever having three arms, one of which is arranged to engage and move the belt-shifting rod, a sheave on one of the other arms of the lever, a pendent latch pivotally connected to the remaining arm of the 60 lever, a weight for swinging the said lever in one direction, a cable connected to the weight and passed over the said sheave, a keeper for engaging and holding the latch against movement in the mentioned direction, a belt-traversing rack, a bar connected to said rack and having a lateral journal, a hub loosely mounted and retained on said journal and having arms one of which is arranged to engage the latch and also having a 65 counterbalance, a tappet for engaging and moving the other arm of the hub, and means for moving the said tappet. 70

4. The combination in a roving frame, of 75 means for shifting a belt, a latch, a connection between the latch and said means, a weight connected with the said connection for moving the belt-shifting means when the latch is released, a keeper for engaging and holding the latch against movement in one 80 direction, a belt-traversing rack, means thereon for moving the latch out of engagement with the keeper, and a device movable at an angle to the belt-traversing rack and arranged to move the said means for moving 85 the latch.

In testimony whereof I have hereunto set my hand in presence of two subscribing witnesses.

MAURICE NOLET.
